FURNACE FOR BIMETALLIC CASTINGS

Simon Kail, East Cleveland, Ohio

Application July 10, 1945, Serial No. 604,136

1 Claim. (Cl. 22—58)

1

This invention relates to apparatus for founding non-ferrous metals and pertains more specifically to a furnace designed primarily for the production of bimetallic castings such as railway journal bearings.

One of the objects of the invention is to provide a furnace having a plurality of plate-like members embodied therein as a structural part thereof, the members being constructed to support the backing piece for the bimetallic casting formed thereon and to constitute with the backing piece a cover for the furnace combustion chamber when arranged in operative position thereon.

Another object of the invention is to construct a mold and heating unit therefor which will accommodate the casting operation with safety and dispatch.

Another object of the invention is to provide a combustion chamber which will effectively pre-heat the backing pieces prior to the time they reach the pouring or casting station of the furnace.

Other objects and advantages more or less ancillary to the foregoing and the manner in which all the various objects are realized will appear in the following description, which considered in connection with the accompanying drawings, sets forth the preferred embodiment of the invention.

Referring to the drawings:

Fig. 1 is a plan view of the furnace with one of the molds and a fragmentary portion of the successive mold shown in place thereon;

Fig. 2 is a sectional perspective view of the furnace and mold, the section being taken on a plane indicated by the line 2—2 in Fig. 1;

Fig. 3 is a view in perspective of a composite bearing typical of one of the forms of bimetallic castings that may be formed in the improved furnace and mold combination;

Fig. 4 is a transverse sectional view through the central portion of the mold and core, the section being taken on a plane indicated by the line 4—4 in Fig. 1; and

Fig. 5 is an enlarged sectional view of the roller supporting structure.

As will be seen in Figs. 1 and 2, the base of the furnace comprises generally a floor 11, side walls 12 and 13 defining a trough 14, ledges 15 disposed in a common plane in the upper portions of the side walls, and vertical webs 16 extending upwardly from the inner marginal edges of the ledges. The base of the furnace is preferably constructed from fire brick though a structural

2

iron frame having heat resisting ceramic liners therein could obviously be used in substitution therefor. The ledges 15 are provided with channels 17 drilled to accommodate the pivotal support of rollers 18 disposed for engagement with and serving as lateral guide means for the depending side walls 19 of a series of plate-like members 20 bridging the top of the furnace. Guide means are provided for support of members 20 in a horizontal plane. In the preferred construction each channel 17 is fabricated with upturned flanges thereon which are drilled to receive the spindles of rollers 21 disposed for engagement with the lower face of the flanged portions 22 of the plate-like members 20. The trough 14 is provided with a heater which, as illustrated herein, comprises a series of jets or burners 24 coupled with a fuel line 25 fed through a mixing valve connected in the usual manner with an air line 26 and oil supply pipe 27.

The top of the furnace trough 14 is normally closed by the plate-like members 20 which are formed with square end portions 28 adapted for intimate engagement with like faces on the molds adjacent thereto. The plate-like members are formed with openings 29 extending through the body thereof for the reception of the backing piece of the composite bearing to be cast. In the mold for the railroad journal bearing (Fig. 3) chosen herein as merely illustrative of one of the forms of composite bearings that may be cast in the apparatus embodying the present invention, the opening 29 is configured to accommodate exposure of the major portion of the shell or backing piece 30 to the burners 24, the side walls defining the opening being further formed to provide ledges to support the flanged side walls 31 of the steel backing piece 30. At each end of apertures 29 the upper face of the plate-like member is formed with concavities or recesses 33 for the reception of core prints 34 formed in a core 35 provided to define with the backing piece 30 the cavity for the bearing metal 36 shown in Fig. 2.

The plate-like members are formed of a suitable refractory material such as graphite carbon or may be made from a chrome nickel steel alloy, the structural design thereof save for wall thicknesses being the same in either case. In operation the plate-like members are placed in end to end relation upon the rollers 21, with the metal backing pieces 30 and cores 35 assembled therein. The line of plate-like members is then moved along the furnace at a rate of speed, consonant with the intensity of the heat-

ing medium, which will bring the successive plate-like members to the desired temperature when they reach the forming station which, as indicated by the character A in Fig. 1 is adjacent the last burner 24 in the trough 14. As the plate-like members pass the station A the bronze or the bearing metal is poured in the cavity defined by one side of the backing piece 30 and the core. The plate-like member is then passed forward to a conveyor (not shown) of any conventional type until the molten bearing metal thereon becomes solidified. If desired, the conveyor may be arranged in circular or oval form to provide a continuous path so that the plate-like members may be unloaded, recharged and moved, while still hot in an unbroken series to the heater trough.

It will be readily recognized that many other non-ferrous metals may be advantageously and economically cast in the apparatus described above, and that the term "bi-metallic casting" as used herein may apply to such operations regardless of whether the non-ferrous metal is bonded to the backing piece. The bronze lined bearing caps constituting the product of the novel furnace herein described are merely representative of the many forms of bonded bi-metallic castings which may be produced.

By coating the steel backing piece with a suitable parting material, integral brass or bronze pieces may be cast on the furnace as described. Thus the utility, economy, and scope of operations are greatly enhanced, and the superior products obtained by this method of casting are made available with low cost equipment.

Although the foregoing description is necessarily of a detailed character, in order that the invention may be completely set forth, it is to be understood that the specific terminology is not intended to be restrictive or confining, and that

various rearrangements of parts and modifications of detail may be resorted to without departing from the scope or spirit of the invention as herein claimed.

5 I claim:

Apparatus for preheating backing pieces for bimetallic castings comprising a furnace having a bottom and side walls defining an elongated trough, burners disposed along said trough, guide means along each side of and parallel to said trough, a series of plate-like members mounted on said guide means for translation along said trough said members bridging said trough and being disposed above said burners, said members having formed therein and extending vertically therethrough generally rectangular apertures, ledge means at each side of said apertures for supporting a flanged backing member, said members having concavities at each end of the apertures therein to form core end supports, said members including end-to-end engaging means for deflecting gases tending to emerge from between the ends of the members.
